UNITED STATES PATENT OFFICE.

CARL ANDREW KINNINGER, OF DAYTON, OHIO, ASSIGNOR OF ONE-HALF TO ARTHUR M. KINNINGER, OF DAYTON, OHIO.

SLEEPER.

Application filed February 28, 1923. Serial No. 621,732.

To all whom it may concern:

Be it known that I, CARL ANDREW KINNINGER, a citizen of the United States, residing at Dayton, in the county of Montgomery and State of Ohio, have invented certain new and useful Improvements in Sleepers, of which the following is a specification, reference being had therein to the accompanying drawing.

10 My invention relates to sleepers.

It is the object of my invention to provide from a single piece of sheet metal a sleeper which may have portions thereof embedded in concrete and other portions 15 adapted to locate the sleeper with respect to the concrete and to attach the beam to the concrete and the sleeper.

It is a further object to provide a broad, rigid bearing and engaging surface for the 20 sleeper.

It is my object to provide a diagonally braced device having arms to be deeply embedded in the concrete and engaging members in engagement with the sides and bottom of the beams to be attached to the concrete.

It is also my object to provide supporting wings to support the device on the fluid concrete and to prevent it rocking and twisting out of position.

It is an additional object to provide a device which may be made out of a single sheet without any waste of material, and which may be bent into the desired position 35 by hands on the job on which such said devices are to be used, thus economizing in packing, storing and the like, and the labor of formation at the factory where such articles are produced.

40 Referring to the drawings, Fig. 1 is a plan view of the device before being bent into shape.

Fig. 2 is a perspective of the device having split ends bent into position.

45 Fig. 3 is a perspective of the device without split ends but bent into position.

Fig. 4 is a perspective of the device with corrugated ends for attachment to the cement base.

50 Referring to the drawings in detail, 1 designates a diagonally connecting member connecting the end members 2 and 3. These end members may be split along the lines 4 and 5 to form supplementary and dividing end members 6 and 7. It will be noted

that this line of division indicated at 4 and 5 is within the ends of 1 so that both 2 and 6 and 3 and 7 are integrally connected to the connecting member 1 and through 1 interconnecting with one another as a one piece structure. In the event that the end members are split at 4 and 5 one of these members may be bent up and the other bent down as preferred.

The cement engaging members 8 and 9 are 65 integrally connected to the end members such as 2 and 3 and through 2 and 3 are integrally connected with 1.

These cement retaining members are bent downwardly as in Figs. 2, 3, and 4. The 70 ends thereof may be curled as at 10 or corrugated as at 11.

The end members may have holes 12 punched therethrough to receive nails so that the sleepers may be nailed to beams. 75

It will also be observed that in case the end members are divided into an end member proper or a supplementary end member that the end member which is not bent up vertically will act as a support on the 80 more or less fluid concrete maintaining the device in position during the setting operation.

I do not desire to limit myself to the particular details as hereinbefore described, 85 but comprehend within my invention a suitable modification thereof for its practice.

Having thus fully described my invention, what I claim as new and desire to secure by Letters Patent, is:—

1. In a sleeper, a connecting member, end members, and depending material engaging members, said end members being made in two parts, one for engagement with a beam 95 and the other for engagement with a supporting surface.

2. In a sleeper, a connecting member, end members at either end thereof, said end members being arranged vertically, the connecting member horizontally and depending material engaging members arranged substantially in the vertical, and a horizontally disposed member on either end of the connecting member adapted to engage 105 with the supporting surface in substantially the same plane as the connecting member.

3. In a sleeper, a blank, a diagonally disposed connecting member, triangular shaped material engaging members on eith- 110

er side thereof, and end members at either end of the connecting member.

4. In a sleeper, a blank, a diagonally disposed connecting member, triangular shaped material engaging members on either side thereof, end members at either end of the connecting member, said end members being divided into two halves.

5. In a sleeper, a rectangular blank, a diagonally disposed connecting portion formed therein, rectangular end members connected on either end thereof, and triangular shaped depending material engaging members connected to the inside of said

15 end members having the sloping side of the

triangular members adjacent the side walls of the connecting member in the blank.

6. In a sleeper, a rectangular blank, a diagonally disposed connecting portion formed therein, rectangular end members connected on either end thereof, and triangular shaped depending material engaging members connected to the inside of said end members having the sloping side of the triangular members adjacent the side walls 20 of the connecting member in the blank, said end members being divided.

In testimony whereof, I affix my signature.

CARL ANDREW KINNINGER.
